CALCULATING MACHINE

John L. Moody, Oakland, Calif., assignor to
 Friden Calculating Machine Co., Inc., a corpora-
 tion of California

Application January 27, 1940, Serial No. 316,005

1 Claim. (CL 235—63)

My invention relates to calculating machines having a shiftable register carriage, and is concerned more particularly with the provision of improved means for restoring the numeral wheels to zero registration.

It is the general object of the invention to provide an improved construction for effecting zero resetting of the register wherein repeated operation of the resetting means cannot occur if the control therefor is held in active position.

Another object of the invention is to provide improved zero resetting means of the character referred to wherein the linkage connection from the zero resetting key to the parts controlled thereby for effecting the resetting operation can be disabled at the conclusion of the operation in spite of the fact that the key is held depressed.

Other objects and advantages of the invention will be apparent from the following description of a preferred embodiment thereof, as illustrated in the accompanying drawing, in which:

Figure 1 is a longitudinal sectional view through a calculating machine embodying my invention.

Figure 2 is a fragmentary plan view of a machine with the carriage and the keyboard removed.

Figure 3 is a side elevation of the right side plate with certain parts shown in section.

Figure 4 is a fragmentary view of the clutch and a portion of the controlling mechanism therefor.

Figure 5 is a fragmentary view of a portion of the shift control mechanism.

Figure 6 is a partial rear elevational view of the machine with certain parts shown in section.

Figure 7 is a fragmentary plan view of a portion of the resetting mechanism.

The invention is disclosed as embodied in a calculating machine having actuating mechanism of the uni-directional, continuous drive cycle type wherein all power driven operations are effected by engagement and disengagement of a single clutch providing the only source of power from the motor of the machine. A calculating machine of this construction is disclosed in the copending application of Carl M. Friden, Serial No. 42,268, filed September 26, 1935 (Pat. No. 2,310,281).

The frame of the machine may include a base 10 (Fig. 1) upon which casing 11 is suitably mounted. Other frame parts include respective left and right side frame plates 12 and 13 which are suitably mounted in spaced-apart relation upon base 10. Side plates 12 and 13 may be con-

nected by various cross brackets 16, 17, 18 and 19 which serve various mechanism of the machine. The register carriage 22 is mounted on the frame brackets 16 and 19 by rollers 23 for endwise shifting movement laterally of the machine in either direction to various ordinal positions as controlled by means described herein-after.

Carriage 22 includes a frame 31 in which numeral wheel shafts 32 are journaled to carry numeral wheels 33 of conventional construction. To transmit increments of value to numeral wheels 33, each shaft 32 extends below the frame 31 and has a ten tooth gear 34 which is actuated by means later described.

Accumulator resetting means

Means are provided on the carriage for resetting the numeral wheels 33 to zero registration including means such as a rack bar 41 mounted for endwise sliding movement in the carriage frame adjacent the upper end of the numeral wheel shafts 32 for cooperation with mutilated gears 42 carried by numeral wheel shafts 32. Adjacent gears 42 are axially offset to cooperate with the adjacent vertically offset racks found on rack bar 41 in the usual manner. The rack bar 41 is moved from its normal position to which it is spring urged in the usual manner to engage gears 42 of any numeral wheel 33 displaced from the zero position and thereby reset the numeral wheels to such a position. Rack 41 may be selectively connected to an actuating bar 46 mounted on the frame 31 for endwise movement by means of interponent 47 (Fig. 7) carried by manual operation handle 48 on rack bar 41. The power operation of actuating bar 46 is described hereinafter.

Revolutions counter

The revolutions counter may comprise numeral wheels 51 on shafts 52 and may be actuated by means of the actuator 54 in the usual manner. Counter numeral wheels 51 may be reset to zero by rack bar 53 similar to the rack bar 41 described above, and adapted for connection with actuating bar 46 by interponent arm 56 (Fig. 7) on manual operation handle 57. The revolutions counter mechanism is conventional in all respects, and a further description is not believed necessary.

Selecting and actuating mechanisms

The values to be introduced into numeral wheels 33 are selected by means of a plurality of

banks or orders of settable value keys 61, only of which banks is illustrated in part in Figure 1. The keys 61 of each bank cooperate with selecting mechanism including spring urged selecting slides 62 mounted for endwise movement to position gears 63 selectively with respect to the stepped teeth 64 of the associated actuating cylinder 66. Cylinders 66 (Fig. 2) for adjacent orders are mounted on actuating shafts 67 having suitable bevel gear connections with a transverse drive shaft 68 which is suitably journaled in side plates 12 and 13. Shaft 68 and shafts 67 are driven cyclically from motor 69 through clutch 71 which may be driven by suitable gearing 72 (Figs. 3 and 4) from the motor shaft 73. Clutch 71 (Fig. 4) may be engaged or disengaged by oscillation of spring-urged clutch pawl or dog 74 mounted for rotation with shaft 68, and with respect to ratchet 76 journaled on shaft 68 and driven by gearing 72. Clutch control lever 77 is pivoted on side plate 13 at 78 to determine engagement or disengagement of the clutch by releasing or engaging the nose of dog 74 in the full cycle position thereon.

The number of increments transmitted to the pair of gears 63 by the associated cylinder 66 during cyclic operation of the clutch is transmitted to square shaft 81 on which gears 63 are mounted. Each shaft 81 extends rearwardly of the machine in the usual manner and carries a spool 82 having bevel gears 83 and 84 for cooperation with the numeral wheel gears 34.

The selective engagement of gears 83 and 84 with gears 34 (Fig. 1) is controlled by strap 85 positioned between the gears and mounted on suitable arms 86 for rocking movement with shaft 87. Thus, rocking of shaft 87 determines transmission of said increments to the numeral wheels 33 and also the direction of entering thereon. Any suitable control means may be provided for rocking the shaft 87 to control digitation operations. Shaft 87 may be centralized by opposed spring-urged centralizing arms 91 cooperating with a central stop 92 and engaging a pin 93 carried by one of arms 86 on which the strap 85 is mounted.

Carriage shift mechanism

The carriage can be shifted in either direction by power driven means controlled by manually operable keys, and this mechanism is of conventional construction. Carriage 22 (Fig. 6) is provided with toothed plate 101 along the rear side thereof for cooperation with shift pins 102 (Figs. 2 and 6) on shift gear 103. Shift gear 103 can be rotated in either direction and receives one-half rotation for each rotation of clutch 71 referred to above. For this purpose, shift gear 103 is connected by reversing gearing to respective gear sleeves 106, 107, the gearing being arranged so that when driven from gear sleeve 106 the rotation is in one direction, and when driven from gear sleeve 107 rotation is in the other direction. The respective gear sleeves 106, 107 (Fig. 2) are slotted for engagement by toothed collars 108, 109 mounted on the rearward ends of a pair of adjacent actuating shafts 67. The collars 108 and 109 are provided with slidable driving connections 110 with the actuating shafts. The sliding movement of collars 108 and 109 is controlled by means of rods 111, 112 which extend forwardly of the machine.

Shift keys 113 and 114 (Fig. 3) for operating the respective controlling rods 111 and 112 have respective pins 115 (Fig. 5) for cooperation with

respective levers 116 and 117. Lever 116 (Figs. 2 and 5) is secured to transverse shaft 118 while lever 117 is secured to sleeve 119 mounted on shaft 118. Both shaft 118 and sleeve 119 are provided with respective depending arms 120 having their lower ends disposed in front of associated rods 111, 112 respectively, to determine operation thereof upon depression of the associated shift key.

10 To enable the drive by depression of the shift key the respective pins 115 (Fig. 3) thereof cooperate with cam slots in a pivoted lever 121 which is pivotally connected at its lower end to the upper end of lever 122 carrying an insulated pin 123 at its lower end. Pin 123 is adapted to close contacts 124 of the motor circuit upon depression of the shift key. Lever 121 is also connected by link 126 (Figs. 3 and 4) with clutch control lever 77 so that such lever is rocked to clutch engaging position upon depression of a shift key.

15 From the foregoing it is seen that the carriage can be shifted selectively in either direction.

Re-setting drive and control mechanism

The means for effecting carriage return and resetting of the registers in the carriage may be effected by operation of key 131 (Fig. 3) which operates to first effect return of the carriage to its leftmost position, and then to reset any registers carried in the carriage. Upon depression of key 131, it is latched in depressed position by a latch slide 132 mounted on side plate 13 for endwise movement. Slide 132 is urged to the left as viewed in Fig. 3 by spring 133 connected to the pivot pin between slide 132 and its supporting and releasing bellcrank 134. The release of latch 132 is referred to hereinafter.

20 Depression of key 131 serves to enable the shifting mechanism to cause shifting of the carriage to its leftmost position, to enable the re-setting drive connection for power resetting of the accumulator and the revolutions counter, as well as to enable the drive. Adjacent its lower end, key 131 is slotted to engage pin 136 on arm 137 carried by a transverse shaft 138 journaled in side plates 12 and 13. Shaft 138 carries arm 141 having a pivotal connection 142 with a forwardly extending pusher arm 143. Pivotal connection 142 is preferably made in the form of an adjustable eccentric to enable adjustment of pusher arm 143. Arm 143 is spring urged in a clockwise direction by a spring 144, so that notched end 146 thereof is in engagement with rod 147.

25 Rod 147 (Fig. 2) is spring urged forwardly by a spring 148 secured to a shifting fork 149 on rod 147 and engaging shiftable toothed collar 150 engageable with slotted hub 151 of a cam 152. Cam 152 operates arm 153 which in turn operates actuating slide 154 for the re-setting operation. Slide 154 cooperates with arm 156 secured on the actuating bar 46 for the resetting operation. Arm 156 is not lowered into engagement with the actuating slide therefor until the end of the shifting operation when the carriage is in the position shown in Figure 6, because of pawl 158 cooperating with ledge 159 to maintain the arm 156 raised as the carriage is moving through its next to leftmost position as viewed from the front of the machine. Thus, upon depression of the return and re-setting control key the resetting drive connection is enabled, but re-setting cannot occur unless the carriage is in

its leftmost position or until it is returned to such position if displaced therefrom.

To enable return of the carriage, pusher arm 143 (Figs. 1 and 2) carries pin 161 which is cooperatively related to depending arm 162 which is secured on shaft 118. Thus, upon rearward movement of pusher arm 143, arm 162, shaft 118, and arm 120 thereon are rocked to shift rod 111 rearwardly and thereby engage the left hand shift.

To enable the drive upon depression of the return clear key 131, roller 166 thereon (Figs. 3 and 4) is adapted for engagement with cam edge 167 of clutch control lever 77, while pin 168 on the key engages under the upper end of lever 77 in the depressed position to prevent raising of the key until the end of the cycle in which detaching occurs. Lever 77 when rocked to clutch engaging position also operates through link 126 and levers 121 and 122 to close contacts 118.

In order to prevent more than one operation of the resetting means at the end of the shifting operation, yieldable over-ride pawl 171 (Fig. 6) which cooperates with shift gear 103 in the leftmost position of the carriage to prevent attempted shifting beyond such position during overdriving of the shift gear 103 has an extension 172 overlying a slide 173 (Figs. 3 and 6) mounted on the bracket 19 for vertical sliding movement. Slide 173 when moved downwardly engages one arm 174 of a bellcrank having a depending arm 175 connected by a link 176, with arm 177 depending from a cross shaft 178. Cross shaft 178 (Figs. 1 and 2) carries an arm 179 having a notched laterally offset end 180 which underlies arm 143. Thus, during a cycle of the machine in which the resetting operation is effected, arm 179 will be operated to lift arm 143 out of engagement with rod 147, so that the rod

147 is restored to its inactive position to disconnect the drive means. Also the lifting movement of arm 143 (Fig. 1) lifts pin 161 out of engagement with arm 162 to disable the control linkage of the left hand shift mechanism. Thus, even though the return-clear key be maintained depressed, only one cycle of resetting operation can occur.

During the resetting cycle, the key 131 is released by the operation of bellcrank 134 by the extension 172 of pawl 171 so that latch 132 is withdrawn. When bellcrank 134 is rocked rearwardly, spring-urged live pawl 181 (Figs. 3 and 6) pivoted on carriage 22 moves in front of bellcrank 134 to prevent re-engagement of latch 132 with key 131 while the carriage remains in its leftmost position.

I claim:

10 In a calculating machine, having a shiftable register, cyclically operable means for effecting return of said register to a predetermined position, coupled with cyclically operable means for performing a resetting operation on said register, and drive means including a cyclically operable clutch and a drive establishing connection for said resetting means driven by said clutch, said resetting means being operable during overdriving of said returning means, a manually operable key, a control linkage from said key to said clutch, a control linkage from said key to said drive establishing connection, means in said last-named linkage spring-urged to active position, and means operated by said returning means for moving said spring-urged means to 15 inactive position to disable the linkage for said drive establishing connection, said means being operable with said key held depressed and with said clutch engaged.

JOHN L. MOODY.
